UNITED STATES PATENT OFFICE.

WILLIAM B. CAMPBELL, OF SEATTLE, WASHINGTON, ASSIGNOR TO REX MANUFACTURING COMPANY, OF KING COUNTY, WASHINGTON, A CORPORATION OF WASHINGTON.

ROTARY PUMP.

Application filed October 12, 1925. Serial No. 62,138.

This invention relates to improvements in pumps and more particularly to rotary pumps of that character embodying a cylindrical housing, having inlet and outlet connections, wherein a rotor equipped with a plurality of radially extending impeller blades operates to draw in and forcibly discharge water from the housing.

It is the principal object of this invention to improve upon pumps of this character by the provision of a pump embodying a minimum number of parts that are subject to wear and which need from time to time to be replaced, and wherein provision has been made for the replacement of all parts or any part that might become worn or damaged.

A still further object resides in the provision of a rotary pump that is reversible in its operation.

In accomplishing these and other objects of the invention, I have provided the improved details of construction, the preferred forms of which are illustrated in the accompanying drawings, wherein—

Figure 1 is a vertical section of a pump embodied by the present invention, the view being taken in a plane perpendicular to the axis of the rotor.

Figure 2 is a vertical section taken on the line 2—2 in Figure 1.

Figure 3 is a perspective view of the rotor removed from the housing.

Referring more in detail to the drawing—

1 designates the pump housing substantially of cylindrical form, and closed at its opposite ends by plates 2—2 secured by a plurality of bolts, or the like, 3. Provided at the top of the housing in spaced apart relation is an inlet 4 and an outlet 5 to which suitable pipe connections, as designated at 6, may be made.

Extending through the face plates 2—2 of the housing is a rotor drive shaft 7 on which a rotor 8 is keyed. The shaft extends through suitably packed glands 9 to prevent leakage. The rotor comprises a plurality of equally spaced, radially extending impeller blades 10 that closely fit along their side edges against the inner faces of the side walls and which are of such length that they will closely approach or engage with the cylindrically formed inner wall surfaces of the housing, such as that surface designated at 11, at the top of the housing between the

openings 4 and 5 and an arcuate surface at the bottom of the housing, designated at 12, which extends through an arc of ninety degrees. At opposite sides of the housing the walls are set out so as to provide for a flow 60 of water between the walls and ends of the impeller blades.

Formed eccentrically with respect to the rotor shaft in the inner faces of the side plates 2—2, are raceways 15 in which roller 65 bearings 16 are contained and on which the out-turned circular flanges 17 of wearing disks 18, that are placed against these walls, are adapted to rotate. These disks have annular seats 19 formed about their 70 periphery for slidably receiving therein the opposite edges of a cylindrical drum which is so disposed as to provide an open space between its lower wall and the housing but which closes the space at the top by a close 75 fit against the surface 11. The drum comprises four slidably joined segments, the upper and lower segments 21 and 22 having arcuate side rails 23 slidably fitted in the seats 19 and to which arcuate cover 80 plates 24 are secured and which have transverse slots 25 therein through which the ends of opposite blades of the rotor extend. The two opposite side segments 26 and 27 are slidably supported at their edges in the seats 85 19 with their ends underlapping the ends of the two other segments in a nonleaking connection. They also are provided with slots through which the rotor blades extend and during rotative movement of the rotor the 90 segments move therewith and relative to each other but maintain closed joints.

Assuming that the device is so constructed, the rotor may be driven by any suitable driving connection with the shaft 7 and as 95 it rotates, water will be trapped between the drum and arcuate surface 12 of the housing and will be forced outwardly through outlet 5. No return or back flow is possible for the reason that the blades are so spaced 100 that one always closes the space between the drum and lower surface of the housing.

Having thus described my invention, what I claim as new therein and desire to secure by Letters-Patent, is:

1. A pump of the character described comprising a cylindrical casing with inlet and outlet openings, a rotor shaft extended concentrically through the casing, a rotor on the said shaft comprising a plurality of 110

radially directed blades extended into close proximity to the casing wall, annular wear plates fitted rotatably to the side walls of the casing, eccentric of the rotor, and provided with peripheral seats, a cylindrical drum fitted within the casing and comprising a plurality of arcuate segments each with a transverse slot through which an impeller blade operatively extends, alternately arranged segments, having arcuate side rails, fitted slidably in the peripheral seats of the wear plates and the intermediate segments having their side edges fitted slidably in said seats and having their end portions reduced in width and fitted slidably between the side rails of the adjacent segments.

2. A pump of the character described comprising a cylindrical casing with inlet and outlet openings, a rotor shaft extended concentrically through the casing, a rotor on the shaft comprising a plurality of radially extending blades terminating in close proximity to the casing wall, circular raceways

formed in the opposite side walls of the casing, eccentric to the rotor, anti-friction rollers operable in said raceways, annular wear plates fitted rotatably to the side walls of the casing each with an outturned annular flange at its inner edge, adapted for support on said rollers and provided, about its outer edge, with an annular seat, a cylindrical drum fitted within the casing and comprising a plurality of arcuate segments each with a transverse slot through which an impeller blade operatively extends, alternately arranged segments having arcuate side rails fitted slidably in the said peripheral seats of the wear plates and intermediate segments having their side edges fitted slidably in said seats and having their end portions reduced in width and fitted slidably between the side rails of the other segments.

Signed at Seattle, King County, Washington, this 10th day of March 1925.

WILLIAM B. CAMPBELL.
